CLAIM

The ornamental design for a scooter, as shown and described.

DESCRIPTION

FIG. 1 is a top, rear, left-side perspective view showing a scooter of my design;

FIG. 2 is a close-up view of a portion thereof;

FIG. 3 is a bottom, front, left-side view thereof;

FIG. 4 is a left-side view thereof;

FIG. 5 is a right-side view thereof;

FIG. 6 is a front view thereof;

FIG. 7 is a rear view thereof;

FIG. 8 is a top view thereof; and,

FIG. 9 is a bottom view thereof.

The dot-dash line in FIG. 2 represents the boundary of the enlarged partial view. All other broken lines are for the purpose of illustrating portions of the scooter that form no part of the claimed design. None of the broken lines form a part of the claimed design.
